MECHANISM FOR SURFACING POLISHING DISKS

Jacob Fine, New York, N. Y.

Application February 28, 1944, Serial No. 524,335

5 Claims. (Cl. 90—24)

In the process of polishing diamonds a metal disk is employed which rotates rapidly, ordinarily in horizontal position. The surface of this disk (except for an area adjacent the center which is ordinarily left smooth) is grooved with fine lines which ordinarily extend in an approximately radial direction but with slight curvature. These grooves serve to hold diamond dust used for cutting and polishing the stone. These disks wear down with use and have to be re-surfaced quite frequently. The re-surfacing by applying the necessary grooves has heretofore been done by hand and demanded considerable skill, so that it has been an expensive operation. This invention relates to a machine whereby this work can be done substantially automatically.

Such a machine may be either an independent machine for receiving the disks removed from the polishing bench or it may take the form of an attachment so that the disks are re-surfaced without being removed from the polishing bench. In either case the disk should be ground smooth before the striping operation. Where a separate mechanism is used, this grinding mechanism may be of any desired type. Where the striping or grooving is carried out without removing the disk from its place on the polishing bench, grinding mechanism will ordinarily be supplied so that the disk can also be ground while in place on the polishing bench. In either case (after the grinding) it is an essential that mechanism be supplied for rotating the disk quite slowly during the time that the striping operation is being carried out. Where the disk is to be re-surfaced in place, this will take the form of separate gearing which may operate through the usual drive.

In order to carry out the striping operation, an arm is pivoted adjacent the edge of the disk which carries at the moving end a cutting point. This arm is of such length that when the cutting point is on the periphery of the disk, the arm is approximately parallel to a tangent drawn to that point. Means is supplied for moving this arm back and forth from the approximate periphery of the disk to the edge of the inner zone which is left smooth and thereby grooves of proper configuration are applied.

I have found it preferable (though not always essential) to have the cutting take place only on the outward stroke, and prefer to have the disk remain stationary during the time that a groove is being cut. The cutting point is then raised and moved outwardly and while this movement is taking place the disk is advanced to the position for the next cut to be made. The grooves

are very fine and quite close together. For example they may be about .001 inch deep and spaced apart .003 inch.

The operation described gives a preferred pattern of grooves on the surface of the disk but other patterns may be used if desired. For example, it is possible to reciprocate the cutting point in and out over the disk and have it cut in both directions and to have the disk moving very slowly but continuously while the cutting is going on; or the disk can move while the point is cutting in one direction and remain stationary while the point is cutting in the other direction. It is also possible to arrange the grooves in one of these manners in such a way that they are spaced part somewhat further than has been indicated and then apply a second set of grooves which come between and intersect them. These are merely details depending on the adjustment of the mechanism but I will describe the mechanism set up so that I get the preferred pattern of slightly curved approximately radial lines.

This invention can readily be understood by reference to the accompanying drawings in which I describe a complete machine for receiving disks removed from the polishing bench. In these drawings, Fig. 1 is a plan view of a mechanism embodying my invention showing a disk in place but with a part of the disk broken away; Fig. 2 is a sectional side view; Fig. 3 is a section on line 3—3 of Fig. 1; Fig. 4 is a detailed view of one of the clamps for gripping the disk, and Fig. 5 is a detailed view showing the manner in which the cutting point is held.

Referring to the drawings, the letter D indicates the disk to be surfaced and this disk is here shown as made integral with a shaft S. It is also understood that the shaft S ordinarily will carry a gear which is not here shown but provision must be made for its accommodation.

The disk D is carried by the rotating table 10 where any desired mechanism is used to hold it. In this case the table 10 is shown as provided with three toothed blocks 12 arranged at even spacing around the periphery. Each of these blocks cooperates with a toothed plate 14, which is tensioned toward the table 10 by a bolt 16 carrying a spring 18. The plates 14 are provided with jaw members 20 for engaging the edge of the disk D. The bolts 16 pass through slots in the table 10 so that the plates 14 can be moved in or out to take care of disks of different diameter.

One or more of the plates 14 is subdivided into two parts as shown in Fig. 3 and a bolt 22 is pro-

vided for moving the jaw member toward the center in order to lock the disk D in place.

The table 10 is open through the center to receive the shaft S and any gear which it may carry. The table is attached to a sleeve 24 which rotates in a bearing ring 26 carried by the main plate 28 of the structure. It is to be understood that this plate 28 is supported by any desired form of framework, not shown.

The sleeve 24 and the table 10 are rotated by a motor 30 carrying a worm 32 cooperating with a gear 34 mounted on the shaft 36. Likewise mounted on the shaft 36 is the eccentric crank 38 which gives a reciprocating movement to the arm 40. The connection between the crank 38 and the arm 40 is by means of a slot and pin as shown in Fig. 1, and by adjusting the position of attachment the degree of angular movement given to the arm 40 can be varied.

The arm 40 is mounted on a shaft 42 which likewise carries the toothed disk 44 to which is connected the horizontal bevelled gear 46. The arm 40 carries a pawl 48 which cooperates with the teeth of disk 44 to advance this disk a predetermined number of tooth spaces (depending on the point of attachment of crank 38) for each reciprocation of the arm 40. A detent 50 prevents the disk 44 from turning in the reverse direction.

A horizontal shaft 52 mounted in a bracket 54 carries at one end a bevelled gear 56 which cooperates with the bevelled gear 46 and at the other end carries a worm 58 which cooperates with a gear 60 carried by the sleeve 24. It will thus be apparent that for each rotation of the shaft 36 the table 10 is rotated a small angular distance during the time that the arm 40 is moving in a clockwise direction and remains stationary during the time that the arm 40 is moving in a counterclockwise position.

The cutting tool is carried by an arm 61 which is pivotally mounted in a bracket 62 and is supported near its outer end by the wheel 64 which moves on a track 66.

Reciprocatory movement is given to the arm 60 by the crank 68 eccentrically mounted on the disk 70 carried by the shaft 36 so that for each rotation of the shaft 36 the arm 61 will make a full reciprocatory movement. It is obvious that mechanism can readily be applied for adjusting the length of the arm 68 or changing its pivotal points to take care of different length strokes but this is not necessary, for if the disk D being finished is smaller than the one shown, the cutting arm simply moves freely during the latter part of its outward movement.

As shown in Fig. 5 the actual cutting tool 72 is clamped in a bracket 74. This tool may have a point of hardened alloy steel but preferably it is provided with a diamond point. The bracket 74 is clamped on the shaft 76 by a collar 78. A torsion spring 80 surrounds the shaft 76 and exerts a strong pressure tending to hold the tip of the cutting tool 72 down on the disk.

In my preferred embodiment the cutting tool contacts with the disk only as it moves out from the center, and mechanism is provided to lift it during the return movement. This mechanism comprises a cam 82 carried by the shaft 36 which cooperates with the cam roller 84. The cam roller 84 is carried by a plunger 86 tensioned toward the cam 82 by the spring 88. The other end of the plunger 86 contacts with the vertical arm of a bell crank lever 90 (see Fig. 3). The horizontal arm of this lever contacts the vertical plunger 92 which passes down through the arm 60. At

its upper end the plunger 92 is bent horizontal as shown at 94 and carries a sleeve 96 having an extension which runs underneath an arm 100 which is preferably formed integral with the tool shaft 5. The cam 82 is so designed that when the arm 60 reaches its outermost position (as shown in Fig. 1) the cam wheel 84 is about to ride up on the cam to operate through the bell crank lever 90 and lift the plunger 92 and thereby lift the cutting tool from the disk to be treated. When the tool is moved in to the point where the cut should start, the cam 82 permits the cutting tool to drop back under the tension of the torsion spring 80 so that as the tool is moved outwardly a cut is formed in the disk that is being finished.

I have not provided any automatic mechanism for stopping the device when a disk D has made a complete rotation, but such a mechanism can be readily be added if it is thought desirable.

While I have illustrated my invention as a separate mechanism for re-surfacing disks removed from the usual polishing benches, it is also possible to correlate the cutting arm with the driving mechanism of the disk in the polishing machine in which it is used, by the simple expedient of connecting proper mechanism to the type of drive already there, so that the desired slow rotation is attained. Whether this is done, or whether the entire separate machine, such as described, is used, the principle employed is the same, for in either case mechanism is supplied for imparting the necessary movement to the cutting point so that it will pass over the surface of the disk and for imparting the necessary slow rotation to the disk. This rotation should be so slow that a point on the edge of the disk will not advance more than .007 inch each time that the cutting arm passes over its surface and preferably not more than about .003 inch for each such pass. Thus even if the machine is operated at a speed to give rapid reciprocation to the cutting arm, it will take a 12-inch disk considerably more than one-half hour to make one revolution.

It is understood that the example given is intended only as an illustration and that the same may be modified in many particulars without departing from the spirit of my invention.

What I claim is:

1. In combination with means for supporting a polishing disk and giving it a rotary movement about its axis, a mechanism for striping the surface of such disk comprising means whereby the disk may be turned throughout 360 degrees about its axis, a cutting arm pivoted outside the zone of the disk, a cutting point carried by the arm in such a way that when the arm is moved over the disk the point will move in a curving but approximately radial direction relative to the disk, means for giving the cutting arm such a movement over the disk, and means for pressing the cutting point against the face of the disk so that it will cut grooves in the surface of the disk.

2. A structure as specified in claim 1, in which the means for giving the disk a rotary movement comprises mechanism whereby the disk is given an intermittent rotary movement and mechanism is supplied for correlating the movement of the cutting arm and the movement of the disk so that the disk remains stationary when the cutting point is pressed against the disk but moves when the cutting point is out of contact with the disk.

3. A structure as specified in claim 1, in which mechanism is supplied so that the cutting point contacts with the disk when moving away from

the center of the disk but does not cut as the cutting arm is moved toward the center of the disk.

4. In combination with means for supporting and rotating a polishing disk, a mechanism for striping the surface of such disk comprising means whereby the disk is given an intermittent rotation, a cutting arm pivoted outside the zone of the disk, a cutting point carried by the arm in such a way that when the arm is reciprocated over the disk the point will move in a curved but approximately radial direction relative to the disk, means for giving the cutting arm such a reciprocatory movement over the disk, means for pressing the cutting point against the surface of 15

the disk while the cutting arm is moving outwardly but for lifting it out of contact with the disk when the cutting arm is moving inwardly, and mechanism for correlating the movement of the cutting arm and the movement of the disk so that the disk remains stationary when the cutting point is in contact with it but moves while the contact point is out of contact with it.

5. A structure as specified in claim 4, in which 10 the means for supporting a polishing disk is formed with a large central aperture so that the mechanism will receive a polishing disk carrying a centrally located shaft.

JACOB FINE.
